UNITED STATES PATENT OFFICE

SAMUEL KRAUS, OF NEW YORK, N. Y., ASSIGNOR TO THE EAGLE PENCIL COMPANY, OF SAME PLACE.

DESIGN FOR A LEAD-PENCIL.

SPECIFICATION forming part of Design No. 18,492, dated July 31, 1888.

Application filed June 22, 1888. Serial No. 277,928. Term of patent 3½ years.

To all whom it may concern:

Be it known that I, SAMUEL KRAUS, of the city, county, and State of New York, have invented and produced a new and original Design for Lead-Pencils, of which the following 5 is a specification.

The sheath itself of the lead pencil is of the usual configuration. Upon it is placed an ornamental pattern surrounding it, and consisting of light spots of small diameter upon a background of contrasting color similar to that which forms the ground of the conventional bandana handkerchief.

In the accompanying drawing, which illustrates the design, A is the lead-pencil, B the

spots, and C the background, which is of the color hereinbefore specified.

What I claim is—

The design herein shown and described, consisting of a lead-pencil the sheath of which 20 has upon it a surrounding ornamental pattern consisting of light spots of small diameter upon a background of contrasting color, as set forth.

In testimony whereof I have hereunto set my hand this 18th day of June, A. D. 1888.

SAMUEL KRAUS.
